O-ALKYL-O-CYCLOALKYL THIOPHOSPHORIC ACID S-PHENYLESTERS

Gerhard Schrader, Wuppertal-Cronenberg, Germany, assignor to Farbenfabriken Bayer Aktiengesellschaft, Leverkusen, Germany, a German corporation
No Drawing. Filed Apr. 10, 1963, Ser. No. 271,878
Claims priority, amendment of May 26, 1962, application Germany, July 28, 1961, F 34,558
12 Claims. (Cl. 260—461)

The present invention relates to and has as its objects new and useful O-alkyl-O-cycloalkyl thiophosphoric acid S-phenylesters which show a remarkable activity against ectoparasites.

O,O-dialkyl-phosphoric acid-S-phenylesters are already known (cf. U.S. patent specification 2,861,876). These phosphorus containing compounds have only a very low activity against ectoparasites. The most active compound of this group is the O,O-diethyl-phosphoric acid-S(p-chlorophenyl)ester of the formula

It has been found that the O-alkyl-O-cycloalkyl thiophosphoric acid-S-phenylesters of the formula

wherein

R₁ stands for lower alkyl with 1 to 4 carbon atoms or lower alkenyl with 1 to 4 carbon atoms,

R₂ stands for cycloalkyl with 5 to 6 carbon atoms,

R stands for halogen, lower alkyl with 1 to 4 carbon atoms or lower alkoxy with 1 to 4 carbon atoms, and

n stands for 1 or 2,

possess a high activity against ectoparasites.

It is very surprising that the compounds according to the invention have a considerably higher activity against ectoparasites than the known compounds which are similar to the compounds of the invention. It is completely surprising that the substitution of a cycloalkyl radical for a lower alkyl radical increases the pesticidal activity of about 10 to 250 times (cf. the table below).

In the above formula of the compounds according to the invention R₁ preferably stands for methyl, ethyl and propyl. R₂ preferably stands for cyclohexyl and cyclopentyl. R preferably stands for halogen, such as chlorine, bromine and fluorine, methyl, ethyl, methoxy and ethoxy.

The following individually mentioned compounds represent a selection of especially suitable compounds which can be used in accordance with the invention:

O-methyl-O-cyclohexyl-thiolphosphoric-acid-S(p-chlorophenyl)-ester,
O-ethyl-O-cyclohexyl-thiolphosphoric-acid-S(p-chlorophenyl)-ester,
O-isopropyl-O-cyclohexyl-thiolphosphoric-acid-S(p-chlorophenyl)-ester,
O-methyl-O-cyclohexyl-thiolphosphoric-acid-S(m-chlorophenyl)-ester,
O-ethyl-O-cyclohexyl-thiolphosphoric-acid-S(m-chlorophenyl)-ester,
O-methyl-O-cyclopentyl-thiolphosphoric-acid-S(p-chlorophenyl)-ester,
O-ethyl-O-cyclopentyl-thiolphosphoric-acid-S(p-chlorophenyl)-ester,

2

O-ethyl-O-cyclohexyl-thiolphosphoric-acid-S(p-chloro-m-methylphenyl)-ester,
O-ethyl-O-cyclohexyl-thiolphosphoric-acid-S(p-chloro-m-methoxyphenyl)-ester.

5 The compounds of the invention can be produced in accordance with known processes, for instance O-alkyl-O-cycloalkyl phosphites can be reacted with phenylsulphenic acid chlorides preferably in the presence of inert solvent such as carbon tetrachloride at temperatures between 0 and about 60°. Representative examples for the preparation of compounds according to the invention are given below.

The phosphorus containing compounds of the invention can be used to combat ectoparasites such as the several types of ticks which belong to the group of mites.

15 For combatting ectoparasites of domestic animals the spray or dip process is preferably used.

In the following the effectiveness of the compounds according to the invention and their superiority over the 20 known chemically similar compounds is established.

The following compounds are prepared and compared:

25 Aqueous dilutions of these compounds are prepared by admixing them with the same amount of dimethyl formamide as an auxiliary solvent adding thereto 20% by weight referred to the active ingredient of a commercial emulsifier consisting of a benzyl hydroxy polyglycol ether containing about 10 to 15 glycol residues, and diluting at least this premixture with water to the desired concentration indicated in the table below.

30 The tests are carried out as follows:

(a) 10 female ticks each of the type *Boophilus microplus* are placed into mull bags which are brought into a solution prepared as described above while moving them continuously. After 1 minute the mull bags are taken off the active solutions and put into glass dishes in which filter paper is placed. The ticks are taken off the mull bags and placed upon dry filter paper. Evaluation occurred after 72 hours. The following results are obtained:

	Compound	Concentration (in percent active ingredient/water)	Killing rate (in percent)
60	(I)	0.025	90
	(III)	0.0001	100
65	(IV)	0.0025	100

The following example relates to the use of the compound of the invention for combatting ticks in the skin of cattle:

70 (b) 8 young head of cattle infested by ticks are sprayed with aqueous suspensions prepared as indicated above containing 0.0030% of compounds III and IV respectively. The living status of the ticks is evaluated

after 72 hours. The killing rate of the ticks is 100% in both cases.

In the following two representative examples for the preparation of compounds according to the invention are given:

Example 1

To a solution of 45 g. (0.25 mol) of O-methyl-O-cyclohexylphosphite (boiling point 124° C./7 mm.) in 150 ccm. of carbon tetrachloride are added at 20° C. with stirring 45 g. of 4-chlorophenylsulphenic acid chloride. Subsequently the reaction mixture is stirred for an hour at 20° C. Subsequently the reaction mixture is washed with a solution containing 3% by weight of sodium hydrogen carbonate until it reacts neutral. The organic layer is separated and dried over anhydrous sodium sulphate and finally distilled. There are obtained 71 g. (89% of the theory) of O-methyl-O-cyclohexyl-S-(4-chlorophenyl)-thiophosphate in the form of a water insoluble colourless oil.

Analysis.—Calculated for a molecular weight of 321: P, 9.6%; S, 10.0%. Found: P, 8.1%; S, 11.0%.

Example 2

96 g. (0.5 mol) of cyclohexyl-ethyl phosphite (boiling point 64° C./0.01 mm. Hg) are added with stirring to a solution of 90 g. of p-chlorophenyl sulphenic acid chloride in 400 ccm. carbon tetrachloride. Subsequently the reaction mixture is stirred for an hour at 20° C. The reaction product is poured into 500 cc. iced water. The organic phase is separated and dried over anhydrous sodium sulphate. The carbon tetrachloride is evaporated and 142 g. of the above shown compound are obtained in a yield of 85% of the theoretical. The new ester is insoluble in water and constitutes a colourless oil, n_D^{22} 1,5332.

Analysis.—Calculated for a molecular weight of 335: Cl, 10.6%; S, 9.6%; P, 9.3%. Found: Cl, 10.2%; S, 9.8%; P, 9.3%.

The toxicity of the compound is 25 mg. per kg. rat (DL₅₀ per os). In the same way the following compounds can be obtained:

O-isopropyl-O-cyclohexyl-thiophosphoric-acid-S(p-chlorophenyl)-ester,
O-methyl-O-cyclohexyl-thiophosphoric-acid-S(m-chlorophenyl)-ester,

O-ethyl-O-cyclohexyl-thiophosphoric-acid-S(m-chlorophenyl)-ester.

I claim:

1. A O-alkyl-O-cycloalkyl thiophosphoric acid-S-phenylester of the formula

in which

R₁ stands for a member selected from the group consisting of lower alkyl with 1 to 4 carbon atoms and lower alkenyl with 1 to 4 carbon atoms,

R₂ stands for cycloalkyl with 5 to 6 carbon atoms, R stands for a member selected from the group consisting of halogen, lower alkyl with 1 to 4 carbon atoms and lower alkoxy with 1 to 4 carbon atoms, and

n stands for a member selected from the group consisting of 1 and 2.

2. A compound according to claim 1 wherein R₁ is lower alkyl, R₂ is cyclohexyl, R is halogen and n is 1.

3. A compound according to claim 1 wherein R₁ is lower alkyl, R₂ is cyclopentyl, R is halogen and n is 1.

4. O - methyl - O - cyclohexyl - thiophosphoric - acid-S(p-chlorophenyl)-ester.

5. O - ethyl - O - cyclohexyl - thiophosphoric - acid-S(p-chlorophenyl)-ester.

6. O - isopropyl - O - cyclohexyl - thiophosphoric-acid-S(p-chlorophenyl)-ester.

7. O - methyl - O - cyclohexyl - thiophosphoric - acid-S(m-chlorophenyl)-ester.

8. O - ethyl - O - cyclohexyl - thiophosphoric - acid-S(m-chlorophenyl)-ester.

9. O - methyl - O - cyclopentyl - thiophosphoric-acid-S(p-chlorophenyl)-ester.

10. O - ethyl - O - cyclopentyl - thiophosphoric - acid-S(p-chlorophenyl)-ester.

11. O - ethyl - O - cyclohexyl - thiophosphoric - acid-S(p-chloro-m-methylphenyl)-ester.

12. O - ethyl - O - cyclohexyl - thiophosphoric - acid-S(p-chloro-m-methoxyphenyl)-ester.
